UNITED STATES PATENT OFFICE

98,712

DESIGN FOR AN EMBROIDERED TEXTILE FABRIC

George Bischof, New York, N. Y.

Application January 6, 1936, Serial No. 60,426

Term of patent 3½ years

To all whom it may concern:

Be it known that I, George Bischof, a citizen of the United States of America, residing in Manhattan, county of New York and State of New York, have invented a new, original, and ornamental Design for an Embroidered Textile Fabric, of which the following is a specification, reference being had to the accompanying drawing, forming part thereof, wherein,

The figure is a plan view of a piece of embroidered textile fabric showing my new design.

I claim:

The ornamental design for an embroidered textile fabric, substantially as shown.

GEORGE BISCHOF.
